GAME BOARD

Dean Burton, Milwaukee, Wis.

Application April 7, 1948, Serial No. 145,572

Term of patent 14 years

(Cl. D34—5)

To all whom it may concern:

Be it known that I, Dean Burton, a citizen of the United States, residing at Milwaukee, in the county of Milwaukee and State of Wisconsin, have invented a new, original, and ornamental Design for a Game Board, of which the following is a specification, reference being had to the accompanying drawing, forming part thereof.

Figure 1 is a front elevational view of the game board showing my new design.

Figure 2 is a side elevational view of Figure 1.

The dominant features of my new design are shown in solid lines in the drawing.

I claim:

The ornamental design for a game board as shown, and described.

DEAN BURTON.
